WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

SYSTEM FOR GOVERNING RAILWAY TRAFFIC.

1,354,254.

Specification of Letters Patent. Patented Sept. 28, 1920.

Application filed November 16, 1915. Serial No. 61,789.

To all whom it may concern:

Be it known that I, WINTHROP K. HOWE, a citizen of the United States, and a resident of the city of Rochester, in the county of Monroe and State of New York, have invented a new and useful System for Governing Railway Traffic, of which the following is a specification.

This invention relates to systems for governing railway traffic, and more particularly to electrically operated devices and controlling circuits therefor constituting a combined signaling and automatic train control system.

One of the objects of this invention is to devise a suitable system of the character specified which will give proper signals in accordance with traffic conditions, and which will govern the electrical condition of appropriate contact rails or ramps by means of which the train will be automatically governed in case these signals are disregarded.

Other objects and advantages will appear as the description of the invention progresses and the novel features of the invention will be particularly pointed out in the appended claims.

In describing the invention in detail, reference is had to the accompanying drawing, wherein I have illustrated a preferred physical embodiment of my invention, and wherein like characters of reference designate corresponding parts throughout the several views, and in which:

Figures 1 and 2 are diagrammatic views of a portion of a track, signals for governing traffic in one direction over this track, ramps for automatically controlling the movement of trains, and the relays and other devices, together with their controlling circuits, which embody this invention. These two figures show adjacent portions of the track and are intended to be placed together end to end with Fig. 2 at the right.

Referring to the accompanying drawing, one track rail 1 of the track is electrically continuous, the separate rails thereof being bonded together; and the other track rail 2 is divided by insulating joints 3 into a series of track sections A, B, C, D and E. At the entrance to the track sections B, C, D and E, hereinafter termed blocks, is a suitable signal for governing traffic in the direction indicated by the arrow X, said signals being

designated S, S¹, S², and S³. These signals 55 may be of any suitable construction, but are shown as so-called light signals, which exhibit different colored lights, such as red, yellow and green, as their indications. Located adjacent to each of said signals is an 60 insulated ramp, designated P, P¹, P² and P³. These ramps are intended to coöperate with suitable contact shoes carried by the train and in some appropriate manner communicate the information concerning the traffic 65 conditions to the train. The contact shoe and automatic train control apparatus may be of any suitable construction, it being merely essential for the operation of this system that the automatic train control apparatus be responsive to different potential differences between the ramps and the track rails, and in the particular arrangement of controlling circuits shown, it is assumed that an automatic train control system of appropriate construction is used so that, when the 70 train encounters a ramp between which and the track rail a high difference of potential exists, the automatic train control apparatus will be restored to its normal or idle condition; that a medium difference of potential 75 will cause the train control apparatus to be held in the position which it then occupies; that a low difference of potential causes the automatic train control apparatus, so far as 80 the control of the speed of the train is concerned, to be set into operation; and that no difference of potential causes the full braking force to be immediately applied. It is to be understood, however, that this selection of voltages is not compulsory and that with other types of train control apparatus other voltages may be used.

Extending along the track are two wires 4 and 5, which are connected to a suitable 95 source of alternating current, as a generator 6, and which serve to supply the power for operating the signals and relays and energizing the ramps. Since the controlling devices and controlling circuits associated 100 with each of the signals S and the ramps P are, with minor exceptions, the same, the parts associated with the signals S¹, S² and S³ will be given the same reference characters as the corresponding parts associated 105 with the signal S, with the distinctive exponents 1, 2 and 3 added thereto.

At one end of each block, preferably

the exit end, the secondary of a transformer 7 is connected by wires 8 and 9 to the track rails 1 and 2. Associated with each signal S are transformers 10 and 11, the first serving to supply power for lighting the red, green and yellow lights of said signal, the other transformer 11 serving to furnish power for operating the different controlling relays. Associated with each ramp P is 10 a transformer 15, one terminal of the secondary of which is connected by a conductor 19 to the continuous track rail 1, said secondary having three taps, 16, 17 and 18 representing high, medium and low voltages, 15 respectively.

To the end of each block, opposite to the end to which the transformer 7 supplies current, is connected a track relay T. These track relays T are shown according to established convention of the type comprising 20 two separate coils or windings 20 and 21, the coil 20 being connected across the track rails 1 and 2, and the coil 21 being connected at one terminal by conductors 22, 23, 24, 25 and 25 to the middle tap 13 of the secondary of the transformer 11 and at the other terminal by conductors 28, 27 and 26 to one terminal tap 14 of the secondary of the transformer 11, marked positive. In order 30 to energize the track relay T and cause its armatures 29, 30, 31, 32 and 33 to be raised it is necessary to supply current to both of its windings 20 and 21, and since one of said windings 21 is permanently connected to a 35 source of current, the energization or deenergization of the other windings 20 determines whether or not its armatures are raised or lowered.

Also associated with each signal S is a 40 relay H, hereinafter termed the home relay, and a relay G hereinafter termed the distant relay, it being understood that these terms are chosen merely for the sake of convenience and do not suggest any particular construction or function of the relays so designated. These relays H and G are shown 45 of the type commonly known as three-position alternating current relays, and comprise two separate coils or windings. The 50 construction and characteristics of this type of relay is well known in the art, and it is deemed unnecessary for a clear understanding of the nature and scope of this invention to describe these relays further than to 55 say that it is necessary to have both of the separate windings of these relays energized in order to operate their armatures, and that the relative polarity at any given instant of the terminals of said windings determines 60 the direction in which said armatures are operated. The separate windings of the relay H are designated 34 and 39, and the winding 34 is permanently connected by conductors 35, 24 and 25, and by conductors 65 38, 37 and 36 to the negative and neutral

taps 12 and 13, respectively, of the secondary of the transformer 11, so that said winding 34 is energized at all times. The controlling circuits for the other winding 39 of the relay H will be set forth fully hereinafter in the description of the operation. The armatures 40, 41, 42, 43 and 44 of the relay H are represented according to established convention and may occupy a position, shown in full lines in the drawing, 70 to the left, this position for the relay H being hereinafter termed the normal position; a middle position, corresponding to the de-energization of the winding 39 and herein-after termed the neutral position; and a position to the right of the position shown in the drawing, this position being hereinafter termed the reverse position.

The separate windings of the distant relay G are designated 46 and 47, the winding 47 being permanently connected by conductors 53, 54, 55, 23, 24 and 25, and by conductors 59, 58, 57, 56, 37 and 36 to the neutral and negative taps 13 and 12, respectively, of the secondary of the transformer 85 11, so that said winding 47 is energized at all times. The armatures 48, 49, 50, 51, 52 of the distant relay G have three different 90 positions indicated and designated the same as the three different positions above mentioned of the home relay H.

Also associated with each signal S is a relay 60, hereinafter designated the stick relay, having two armatures 61 and 62, which are connected by and arranged to be operated by a push button 63 or other suitable manually operable device. The circuits controlled by the armatures 61 and 62 of the stick relay 60 will be pointed out fully hereinafter.

Extending the full length of the track is a common wire 100, which is connected by a conductor 99 to the neutral tap 13 of the secondary of each of the transformers 11, and for convenience and clearness some of the operating circuits set forth hereinafter will be traced from the common wire 100 at one point back to the common wire 100 at another point, it being obvious that the common wire serves to complete the circuits thus 110 traced.

Operation.—The operation of the signals S will be considered first, and it will be assumed that a train commences at the block A, and as it passes along the track, the different circuits and different signals set up behind it will be traced at length. When the train enters the block B its wheels and axles shunt the winding 20 of the track relay T and cause the armatures of said track relay to drop. The dropping of the armatures 30 and 31 of the track relay T causes a reversal of the armatures of the home relay H by reason of the fact that the polarity of the winding 39 of said home 125 relay H will be reversed. The dropping of the armatures 30 and 31 of the track relay T causes a reversal of the armatures of the home relay H by reason of the fact that the polarity of the winding 39 of said home 130

relay is changed. To illustrate, the circuit for normally energizing the winding 39, when the track relay T is energized, is as follows:

5

CIRCUIT NUMBER ONE.

Commencing at the neutral tap 13 of the secondary of the transformer 11, conductors 25, 24, 23, 55 and 64, winding 39, conductors

10 65, 66 and 67, armature 49 of the distant relay G normal, conductors 68 and 69, armature 30 of the track relay T in its upper position, and conductors 70, 27 and 26 to the positive tap 14.

15 The circuit of reversed polarity for energizing the winding 39 is as follows:

CIRCUIT NUMBER TWO.

Commencing at the neutral tap 13, thence 20 as in circuit number one to the armature 30 of the track relay T, thence by conductor 71 to the armature 31 of the track relay T in its lower position, and conductors 72, 57, 56, 37 and 36 to the negative tap 12.

25 When the armatures of the home relay H are reversed, the armature 40 closes a stick circuit for the winding 39 of said relay as follows:

CIRCUIT NUMBER THREE.

Commencing at the neutral tap 13, conductors 25, 24, 23, 55 and 64, winding 39, conductors 65 and 73, armature 40 reversed, conductor 74, armature 32 of the track relay 35 T in its lower position, and conductors 75, 56, 37 and 36 to the negative tap 12.

By reason of this stick circuit number three the armatures of the home relay H will be held in their reversed position so long as the 40 track relay T is deenergized, that is, so long as any portion of the train occupies the block B. To understand the controlling effect produced on the signal S by the reversal of the armatures of the home relay 45 H, it seems desirable to trace the circuit for the green lamp G, which is normally closed, said circuit being as follows:

CIRCUIT NUMBER FOUR.

50 Commencing at one terminal of the secondary of the transformer 10, conductor 76, armature 44 of the home relay H normal, conductor 77, armature 48 of the distant relay G normal, conductor 78, green lamp G, and conductors 81 and 82 back to the other terminal of the secondary of the transformer 10.

When the armature 44 of the home relay H is reversed it interrupts the circuit for the 60 green lamp number four hereinbefore traced, and closes a circuit for the red lamp as follows:

CIRCUIT NUMBER FIVE.

65 Secondary of the transformer 10, conductor

76, armature 44 reversed, conductor 83, red lamp R and conductors 84 and 82 back to the secondary of the transformer 10.

From the foregoing it can be seen that when the train enters the block B the green 70 lamp in the signal S is extinguished and the red lamp lighted, thereby changing the aspect of the signal S from proceed to stop.

As the train proceeds and enters the block C it causes the deenergization of the track 75 relay T¹, and the dropping of the armatures 30¹ and 31¹ of the track relay T¹ causes a reversal of the armatures of the home relay H¹ in the same way as hereinbefore described in connection with the home relay 80 H, and thereby causes a red light to be displayed at the signal S¹. Likewise the stick circuit for the home relay H¹ analogous to circuit number three for the home relay H, is set up, so that this red light is maintained 85 so long as any portion of the train remains in the block C.

The armature 29¹ of the track relay T¹ interrupts a circuit for normally energizing the winding 46 of the distant relay G, said 90 circuit being as follows:

CIRCUIT NUMBER SIX.

Commencing at the common wire 100, conductors 99, 24, 23, 55, 54 and 85, winding 46, 95 conductor 86, armature 29¹ of the track relay T¹ in its upper position, conductors 87¹ and 88¹, armature 42¹ of the home relay H¹ normal, conductors 89¹ and 26¹, positive tap 14¹, secondary of the transformer 11¹, neutral 100 tap 18¹ and conductors 25¹ and 99¹ back to the common wire 100.

The deenergization of the winding 46 of the distant relay G causes the armatures of said relay to assume their neutral position, 105 and the armature 49 of said distant relay G interrupts the circuit number two which at that time is holding the armatures of the home relay H reversed, whereupon said armatures of said home relay H move to their 110 neutral position, providing the train has entirely left the block B. The dropping of the armature 40 to its neutral position breaks the circuit number three, but the armature 44 in its neutral position does not interrupt 115 the circuit number five for the red lamp R, since the contact cooperating with the armature 44 is constructed so as to make contact with said armature in both its reversed position and its neutral position. 120

From the foregoing it can be seen when the train has entirely passed from the block B into the block C a red light is displayed at the signal S and also at the signal S¹.

As the train proceeds and enters the block 125 D it causes a deenergization of the track relay T² and the dropping of its armatures. The armatures 30² and 31² cause a reversal of the armatures of the home relay H² in the same way as hereinbefore described, and 130

the armature 32² establishes the stick circuit, analogous to the circuit number three, for the home relay H². The reversal of the armatures of the home relay H² extinguishes the green lamp G and lights the red lamp R at the signal S² in the same way as before explained. The armature 29² of the track relay T² interrupts a circuit analogous to circuit number six, for the distant relay G¹ 10 and causes its armatures to assume their neutral position, with the same effects as hereinbefore described in connection with the distant relay G, principally the moving of the armatures of the home relay H¹ to 15 their neutral positions. When the armature 41¹ of the home relay H¹ moves to its neutral position and the train has entirely left the block C, so that the track relay T¹ is energized, a circuit for energizing the winding 46 of the distant relay G of a polarity 20 opposite to its normal polarity, is established as follows:

CIRCUIT NUMBER SEVEN.

25 Commencing at the common wire 100, conductors 99, 24, 23, 55, 54 and 85, winding 46 of the distant relay G, conductor 86, armature 29¹ of the track relay T¹, conductors 87¹ and 90¹, armature 41¹ in its neutral position, 30 conductors 91¹ and 36¹, negative tap 12¹ of the secondary of the transformer 11¹, neutral tap 13¹, and conductors 25¹ and 99¹ back to the common wire 100.

It can be seen that the last traced circuit 35 is of different polarity than the circuit number six for normally energizing the winding 46 of the distant relay G, and, consequently, the armatures of said distant relay G are reversed. The armature 49 in its 40 reversed position contacts with conductor 94, which is connected to conductor 66, and since the track relay T is energized, the normal circuit number one for energizing the winding 39 of the home relay H is established, and the armatures of said home relay 45 H are moved to their normal position, as shown in the drawing. The armature 44 of the home relay H interrupts the circuit number five for the red lamp R; and, remember- 50 ing that the armature 48 of the distant relay G is in its reversed position, a circuit for lighting the yellow lamp Y is established as follows:

CIRCUIT NUMBER EIGHT.

55 Secondary of the transformer 10, conductor 76, armature 44 normal, conductor 77, armature 48 reversed, conductor 92, yellow lamp Y, and conductors 93, 81 and 82 back to the 60 secondary of the transformer 10.

From the foregoing it can be seen that when the train occupies the block D a red light is displayed at the signals S¹ and S² and a yellow light is displayed at the signal 65 S. That is, behind the train is displayed a

caution signal and two danger or stop signals, this arrangement being known in the art as a one block overlap.

Next, assume that the train proceeds into the block E. A red light is displayed at 70 the signals S³ and S², and a yellow light is displayed at the signal S¹, as can be readily seen from the foregoing description. The armature 48¹ of the distant relay G¹ is moved to its reverse position to close the 75 circuit for the yellow lamp Y at the signal S¹. The armature 49¹ is also moved to its reverse position to close the break in the circuit, analogous to circuit number one, which energizes the coil 39¹ of the home relay H¹; and since the block C is not occupied and the armature 30¹ of the track relay T¹ is in its upper position, this circuit is completed and causes the armatures of the home relay H¹ to assume their normal 80 position, as shown in the drawing. The movement of the armature 41¹ of the home relay H¹ to its normal position breaks the circuit number seven for energizing the winding 46 of the distant relay G with current of a polarity opposite to its normal 90 polarity, and closes the circuit number six for energizing said winding 46 with current of the normal polarity, so that the armatures of the distant relay G are restored 95 to their normal position, thereby breaking the circuit number eight for the yellow lamp Y of the signal S and closing circuit number four for the green lamp G of the signal S.

From the foregoing description, taken in connection with the circuits illustrated in the drawing, the operation of the signals will be apparent to one skilled in the art of railway signaling; but it is also contemplated according to this invention to provide ramps suitable for governing an automatic train control system so as to enforce obedience to these signals, and this invention further contemplates in controlling the 105 electrical condition of these ramps by means of the same relays used for controlling the signals.

To enable a clear understanding of the controlling circuits for the ramps P, it will 115 be assumed that a train occupies the block D, having passed through the blocks A, B and C and having placed the armatures of the different home and distant relays in position to display two stop signals and a caution 120 signal behind it. At the signal S², the armatures of the home relay H² at this time are reversed and the armatures of the distant relay G² are normal. At the signal S¹, the armatures of both the home relay H¹ and the 125 distant relay G¹ are neutral. At the signal S, the armatures of the home relay H are normal and the armatures of the distant relay G are reversed. Assume that a following train is in the block A and is about to 130

enter the block B. Before the first pair of wheels and axle of this following train enter the block B, the contact shoe carried by that train engages the ramp P. At this time a high difference of potential exists between the ramp P and the track rail 1 according to the following circuit.

CIRCUIT NUMBER NINE.

- 10 Commencing at the ramp P, conductor 101, armature 33 of the track relay T in its upper position, conductor 102, high voltage tap 16 of the transformer 15 and conductor 19 to the track rail 1.
- 15 When the first pair of wheels and axle of the following train enter the block B the track relay T is shunted and its armature 33 drops, thereby interrupting the circuit number nine; and, remembering the positions of 20 the armatures of the home and distant relays H and G, a circuit for creating a low difference of potential between the ramp P and the track rail 1 is established as follows:

CIRCUIT NUMBER TEN.

- 25 Commencing at the ramp P, conductor 101, armature 33 of the track relay T in its lower position, conductors 103 and 104, armature 51 of the distant relay G reversed, conductors 105 and 106, low voltage tap 18 of the transformer 15 and conductor 19 to the track rail 1.

30 This low difference of potential between the ramp P and the track rail 1, in accordance with the characteristics of the automatic train control system which is assumed to be used with the trackway circuits shown and hereinbefore described, causes the speed of the following train to be controlled in any 35 appropriate way, so as to be brought to a stop, or to a safe low speed, by the time it reaches the end of the block B. The signal S¹ indicates stop, but assume that the engineer of the train for some reason fails to 40 bring the train to a stop and said train enters into the block C. At this time, the track relay T¹ being deenergized and its armature 33¹ in its lower position, there will exist no difference of potential between the ramp P¹ 45 and the track rail 1, since the armature 51¹ of the distant relay G¹ is in its neutral position, and interrupts the circuit analogous to the circuit number ten, and since the armature 43¹ of the home relay H¹ is in its 50 neutral position. Consequently, in accordance with the characteristics of the automatic train control system, the emergency brakes will be immediately applied when the following train attempts to enter the 55 block C contrary to the stop indication of the signal S¹.

60 To bring out one further feature of the controlling circuits shown and hereinbefore described, it is assumed that a train is in the block A and about to enter the block B, and

that the trackway for at least three blocks ahead of this train is clear so that the signal S displays a green light and indicates proceed. Under these conditions the armatures of the home and distant relays H and G are 70 in their normal positions as shown; and when the first pair of wheels and axle of the train enter the block B a medium difference of potential will be established between the ramp P and the track rail 1 according to 75 the following circuit:

CIRCUIT NUMBER ELEVEN.

80 Commencing at the ramp P, conductor 101, armature 33 of the track relay T in its lower position, conductors 103 and 107, armature 52, normal, conductor 108, medium tap 17 of the transformer 15 and conductor 19 to the track rail 1.

85 Incidentally, it may be noted that a circuit analogous to this circuit number eleven is established when a train passes from the block C into the block D, while another train occupies the block D; but this condition is hypothetical, since the following train could 90 not pass the danger signal at the signal S¹ without being automatically stopped, and hence could not get as far as the signal S² while the block D was occupied.

95 According to the characteristics of the automatic train control system which is assumed to be used with the particular arrangement of circuits shown and described, this medium voltage holds the parts of said train control system in the positions that 100 they then occupy.

100 It sometimes happens that two or more motor cars or locomotives, each equipped with the automatic train control apparatus, are included in the same train; and it is 105 preferable to connect the train control apparatus on these different cars or locomotives by a continuous conductor or bus so that the apparatus on these different cars will be restored simultaneously to their normal positions. It may also happen that such 110

115 a train will be longer than a block, and that while the contact shoe of one locomotive is in contact with one ramp, the contact shoe of another locomotive is in contact with another ramp in the rear. There is a serious difficulty which arises under such conditions, and it is the purpose of the circuit shown and described to remedy this difficulty.

120 This difficulty is that, when a train enters a block in violation of a stop signal and should be automatically stopped, there would be, without some special arrangement of circuits other than those so far described, a difference of potential between the 125 next ramp at the rear and the track rails, which difference of potential would energize the bus on the train and prevent the emergency application of the brakes. To illustrate, assume a train in the block D, the sig- 130

6
nals S^1 and S^2 being at danger and the signal S at caution for the reasons hereinbefore set forth; and assume that another train, which is longer than the block B, approaches the signal S^1 , and for some reason fails to observe this signal and enters the block C. Under these conditions, the armatures of the distant relay G are in their neutral positions, because the armature 29¹ of the track relay T¹ interrupts the circuit for energizing the winding 46 of said relay. The armatures of the home relay H are in their reverse positions, since they were moved to this position when the following train entered the block B, and since they are held in the reverse position by the stick circuit number three. With the armatures of the home relay H and the distant relay G in the positions just described, a low difference of potential exists between the ramp P and the track rail 1 according to a circuit as follows: Commencing at the ramp P, conductor 101, armature 33 of the track relay T in its lower position, conductors 103 and 107, armature 52 of the distant relay G neutral, conductor 122, armature 43 of the home relay H reverse, conductors 123 and 106, low voltage tap 18 of the transformer 15 and conductor 19 to the track rail 1. This low difference of potential is sufficient to energize the bus and prevent the emergency application of the brakes.

The wiring connections associated with the block C between the signals S^1 and S^2 illustrate those which are used when a block is shorter than the length of trains such as run over the trackway. To explain how this arrangement of circuits prevents a ramp, as P^1 , being energized when a train attempts to enter a block, as the block D, with the next block ahead, as E, occupied, assume a train passes into blocks B and C and for some reason enters block D, this train being long enough so that its rear end is opposite ramp P^1 . Under these conditions, the armatures of the distant relay G¹ are neutral and that the armatures of the home relay H¹ are reversed. Under these conditions the partial circuit for the ramp P^1 is as follows: Commencing at the ramp P^1 , conductor 101¹, armature 33¹ of the track relay T¹, conductors 103¹ and 107¹, armature 52¹ of the distant relay G¹ neutral, conductor 109¹, armature 43¹ of the home relay H¹ reverse, conductor 110¹, conductors 111², or 112², armature 45² of the home relay H² normal or reversed, conductors 113² and 106², low voltage tap 18² of the transformer 15² and conductor 19² to the track rail 1.

60 From this last traced circuit it can be seen that the low difference of potential between the ramp P^1 and the track rail 1 is controlled by the home relay H¹ as well as by the home relay H¹ and the distant relay 65 G¹; and under the particular conditions as

sumed, that is, with a train in the block E and where the emergency application of the brakes should be given when the following train attempts to enter the block D, the last above traced circuit is interrupted at the 70 armature 45² of the home relay H², since the armatures of this home relay H² are in their neutral positions. This latter statement may not be obvious, and to explain, reference is made to circuits numbers one, 75 two, three and six. From analogy to these circuits it can be seen that the armatures of the home relay H² were reversed when the train now assumed to be ahead in the block E passed the signal S^2 , by breaking circuit 80 number one and establishing circuit number two, that when the armatures of said home relay H² were reversed they were held in their reverse position by the stick circuit number three, and that as soon as the train left the block D, said stick circuit was interrupted and the home relay H² placed under the control of the distant relay G².

In this way, low difference of potential is cut off from the ramp P^1 , so that this low 90 difference of potential cannot interfere with the proper emergency application of the brakes, in case a train attempts to enter the block D while the block E is occupied by another train.

95 It may happen that an engineer will wish, for some reason, to pass a danger signal without having the automatic train control apparatus set into operation, as for instance, because of the failure of the signal; and for 100 this purpose the push button 63, the relay 60 and its armatures 61 and 62 are provided. Assume that a train occupies the block C and that another train is in the block A about to enter the block B. Then, for the 105 reasons hereinbefore explained, the red lamp R at the signal S will be displayed, and as soon as the train enters the block B no difference of potential will exist between the ramp P and the track rail 1. Also, the 110 armatures of both the home and distant relays H and G are in their neutral positions. The engineer or motorman of the following train, wishing to pass the signal S, presses the push button 63 and raises the armatures 115 61 and 62 to their upper position. The armature 62 in its upper position establishes a circuit for energizing the winding 39 of the home relay H, which causes the armatures of said home relay to be moved to their 120 reverse position, said circuit being as follows:

CIRCUIT NUMBER TWELVE.

125 Commencing at the neutral tap 13 of the transformer 11, conductors 25, 24, 23, 55 and 64, winding 39 of the home relay H, conductors 65, 115, armature 62 in its upper position, conductors 116 and 117, armature 50 of the distant relay G neutral, conductors 130

118, 58, 57, 56, 37 and 36 to the negative tap 12 of the transformer 11.

When the armature 43 of the home relay H is reversed a low difference of potential is 5 created between the ramp P and the track rail 1 according to a circuit as follows:

CIRCUIT NUMBER THIRTEEN.

Commencing at the ramp P, conductor 101, 10 armature 33 of the track relay T in its lower position, conductors 103 and 107, armature 52 of the distant relay G neutral, conductor 122, armature 43 of the home relay H reverse, conductors 123 and 106, low voltage 15 tap 18 of the transformer 15 and conductor 19 to the track rail 1.

It should be noted that this last traced circuit number thirteen is not established until the track relay T is deenergized; and 20 also that the reversal of the armature 40 of the home relay H, which ordinarily would establish the stick circuit number three, does not establish this stick circuit until the 25 track relay T is deenergized. The train, however, is still in the block A and can only enter the block B, without being automatically stopped, while the armatures of the 30 home relay H are reversed. It is contemplated that the re-set button 63 will be disposed at some convenient point along the trackway in such position that the motor-man or engineer may gain access to it by breaking a seal or operating a lock without leaving the cab; and with this location of 35 the re-set button it is necessary to hold the re-set button raised, after it has once been raised, while the train proceeds and enters the block B, whereupon the dropping of the armature 32 of the track relay T closes 40 the stick circuit number three. This holding of the re-set button 63 is accomplished by the stick relay 60 and the armature 61; and when the armature 61 is raised, the 45 relay 60 is energized and holds both the armatures 61 and the armatures 62 in their upper positions, the energizing circuit for the stick relay circuit being as follows:

CIRCUIT NUMBER FOURTEEN.

50 Commencing at the positive tap 14 of the transformer 11, conductors 26, 27 and 70, armature 30 of the track relay T in its upper position, conductors 69 and 121, relay 60, conductor 120, armature 61, conductors 119 and 117, armature 50 of the 55 distant relay G in its neutral position, conductors 118, 58, 57, 56, 37 and 36 to the negative terminal 12 of the transformer 11.

In this way, the armature 62 is held in 60 its raised position, after it has once been raised, by operating the re-set key 63, until the train enters the block B and causes the deenergization of the track relay T and the breaking of the circuit number fourteen 65 for the stick relay 60. From the foregoing

it can be seen that an engineer or motor-man may key by a stop signal; but the special arrangement of circuits shown is such that the entire control of the train is not restored to the engineer; but, on the contrary, the train is placed under the control of the speed control apparatus which operates to bring it to a stop at the end of the block into which the engineer has just keyed.

The system embodying this invention has been shown as designed to be operated by alternating current, thereby deriving the advantage of having the system unaffected by stray direct current; but it is to be understood that simple changes, obvious to those skilled in the art of railway signaling, can be made whereby direct current may be used as the operating medium for this system. Various other changes in the particular arrangement of the controlling circuits, may be made without departing from this invention, and the system shown may be combined with the features of other systems; and I do not wish to be restricted to the details of the circuits shown and described.

Although I have particularly described the construction of one physical embodiment of my invention, and explained the operation and principle thereof, nevertheless, I desire to have it understood that the form selected is merely illustrative, but does not exhaust the possible physical embodiments of the idea of means underlying my invention.

What I claim as new and desire to secure by Letters Patent of the United States, is:

1. In a system for controlling railway traffic, in combination: a plurality of electrically isolated track circuited blocks each having a track relay; an insulated ramp at the entrance to each of said blocks, a source of electrical energy for establishing a difference of potential between each of said ramps and the track rails; means governed by the track relay of the block next in advance of the block corresponding to a ramp for interrupting the connection between the corresponding source and that ramp; and manually operable means for establishing a connection between said ramp and said source independently of said means and for maintaining such connection until a passing train has left the block corresponding to said ramp.

2. In a system for controlling railway traffic, in combination: a plurality of electrically isolated track circuited blocks, each having a track relay; a signal at the entrance of each of said blocks, an insulated ramp at the entrance of each of said blocks; sources of electrical energy for establishing different differences of potential between each ramp and the adjacent track rails; and

means for controlling the aspects of said signal and for making and breaking the connection between said sources and said ramp, said means being governed by the 5 track relays of one or more of the blocks succeeding said signal and ramp and causing different controlling conditions of said ramp and different aspects of said signal depending on the number of unoccupied 10 blocks in advance thereof.

3. In a system for controlling railway traffic, in combination: a plurality of electrically isolated track circuited blocks, each having a track relay; an insulated ramp 15 at the entrance of each of said blocks; a source of electrical energy for creating a difference of potential between each of said ramps and the track rails; and means for controlling the connection between said source and said ramp governed by the track 20 relays associated with the next two blocks in advance of the corresponding block.

4. In a system for controlling railway traffic, in combination: a plurality of track 25 circuited blocks, a signal at the entrance to each block; a polarized relay for selectively controlling the caution and clear aspects of said signal; an energizing circuit for said relay; means controlled by the track circuit 30 of the next block in advance of the corresponding block for controlling the continuity of said circuit, and means controlled by a track circuit on the second block in advance of the corresponding block for determining the polarity of said circuit. 35

5. In a system for controlling railway traffic, in combination: a plurality of track circuited blocks; a signal at the entrance to each block; a polarized three position relay 40 for selectively controlling the stop aspect and proceed aspects of said signal, a circuit for controlling said relay; means controlled by the track circuit of the corresponding block for determining the polarity of said circuit, and means controlled by the track 45 circuit of the next block in advance for controlling the continuity of said circuit.

6. In a system for controlling railway traffic, in combination: a plurality of track 50 circuited blocks; an impulse device associated with each block and adapted upon the entrance of a train into the corresponding block to have its controlling condition changed from a safety condition to either of 55 two distinctive train controlling conditions; and circuits and controlling apparatus for governing the controlling conditions of each impulse device, said circuits and apparatus acting when a train is present on any one of 60 said blocks to place the impulse device of the next block in the rear in one of its distinctive train controlling conditions and the impulse device of the second block in the rear in its other distinctive train controlling condition. 65

7. In a system for controlling railway

traffic, in combination: a plurality of blocks each provided with a normally closed track circuit and a track relay; an impulse device associated with each block and encountered by a passing train prior to its entrance into 70 that block; a high voltage source of current associated with each block; a circuit for energizing each impulse device including the corresponding high voltage source and controlled by the front contact of the track 75 relay of the corresponding block; a lower voltage source of current associated with each block; a second circuit for energizing each impulse device, including the corresponding lower voltage source and controlled by the back contact of the track relay 80 of the corresponding block; a relay for controlling said second circuit; and an energizing circuit for said relay controlled by the track relay of the next block in advance. 85

8. In a system for controlling railway traffic, in combination: a plurality of track circuited blocks each having a track relay; an impulse device located adjacent to the entrance end of each block; partial circuits for 90 determining the controlling condition of each impulse device and each including a back contact of the track relay of the corresponding block; a relay for selectively controlling said partial circuits; and a circuit 95 for energizing said relay including a front contact of the track relay of the next block in advance of the corresponding block.

9. In a system for controlling railway traffic, in combination: a plurality of track 100 circuited blocks; impulse transmitting means located adjacent to the entrance end of each block and adapted to transmit distinctive controlling impulses to a passing vehicle; circuits associated with each impulse transmitting means for determining the nature of the controlling impulses transmitted thereby; a polarized three-position relay for controlling each of said circuits; a circuit for controlling said relay; and means governed by the track circuits of the blocks for rendering the continuity of said circuit dependent on the presence or absence of a train in the next 105 block in advance of the corresponding block 110 and its polarity on the presence or absence of a train in the second block in advance of the corresponding block. 115

10. In a system for controlling railway traffic, in combination: a plurality of track 120 circuited blocks; a ramp located adjacent to the entrance end of each block; sources of current of different potential associated with each ramp; partial circuits associated with each ramp and each including one of 125 said sources; and relays and controlling circuits governed by said track circuits for opening and closing said partial circuits selectively, said relays and controlling circuits causing the potentials applied to a 130

plurality of the ramps in the rear of a train commencing with the ramp next after the ramp at the entrance to the block occupied by said train to increase from zero by 5 successive steps in accordance with the distance separating said ramps from said train.

11. In a system for controlling railway traffic, in combination: a plurality of track 10 circuited blocks each having a track relay; an impulse device associated with each block; a source of current; a circuit including said source for placing each impulse device in condition to permit a train to pass 15 without being stopped; a relay controlled by the track relay of the block next in advance of the block corresponding to each impulse device for controlling the corresponding circuit; and manually controlled 20 means having its initial operation dependent on said relay being deenergized for establishing an auxiliary circuit for said impulse device including said source, said means also acting to maintain said auxiliary 25 circuit established until the track relay of the block corresponding to the associated impulse device is energized.

12. In a system for controlling railway traffic, in combination: a railroad track; 30 impulse devices located at intervals along the track; trackway circuits and apparatus for rendering the controlling condition of each impulse device dependent upon the extent of unoccupied track in advance thereof; each impulse device when a train is 35 within a predetermined distance in advance thereof being caused to assume a stopping condition; and manually controlled means associated with each impulse device and 40 capable of being operated when the corresponding impulse device is in its stopping condition for governing said circuits and apparatus to change the controlling condition of the corresponding impulse device 45 from its stopping condition to another proceed controlling condition, said means after

each manual operation being automatically maintained in its operated condition until a passing train has advanced a certain distance.

50

13. In a system for controlling railway traffic, in combination: a railroad track divided into blocks; a traffic controlled impulse device associated with each block; an auxiliary circuit for energizing each impulse device; a manually operable circuit controller along the track for establishing said auxiliary circuit; an electromagnetic device adapted when energized to maintain said circuit controller closed; said circuit 60 controller automatically opening when released unless maintained closed by said device; and a circuit governing said device and controlled by the track relay of the corresponding block.

65

14. In a system for controlling railway traffic, in combination: a railroad track divided into blocks; a traffic controlled impulse device associated with each block; a source of current and a circuit for energizing each impulse device; a relay for controlling said circuit; a manually operable circuit controller along the track; an energizing circuit for said relay including 70 said circuit controller; and a stick circuit 75 for said relay including a back contact of the track relay of the corresponding block.

15. In a system for controlling railway traffic, in combination: a railroad track divided into blocks; a traffic controlled impulse device associated with each block; an auxiliary circuit for energizing each impulse device; a relay for controlling said auxiliary circuit; a manually operable circuit controller along the track; an energizing circuit for said relay including 80 said circuit controller; and a stick circuit 85 for maintaining said relay energized after it has been initially energized until the passing train has advanced a certain distance. 90

WINTHROP K. HOWE.
